UNITED STATES PATENT OFFICE.

PHILIP DUFFY, OF WEST DULUTH, MINNESOTA.

JOURNAL-BOX BEARING.

1,335,668.

Specification of Letters Patent. Patented Mar. 30, 1920.

Application filed May 20, 1918. Serial No. 235,558.

To all whom it may concern:

Be it known that I, PHILIP DUFFY, a citizen of the United States, residing at West Duluth, in the county of St. Louis and State 5 of Minnesota, have invented certain new and useful Improvements in Journal-Box Bearings, of which the following is a specification.

This invention relates to improvements in 10 journal boxes, and it is the principal object of the invention to provide a novel form of bearing therefor formed of fibrous material and being capable of withstanding material wear and also reducing friction to a minimum, thus preventing the overheating of 15 the parts or the damaging of the shaft received therein.

Another and equally important object of 20 the invention is to provide a bearing having means for distributing lubricant to the entire surface of the shaft.

The improvements in the details and arrangement of parts will be apparent from 25 an inspection of the accompanying drawings, in connection with the specific description hereinafter contained, and wherein the preferred embodiment of the invention is disclosed for the purpose of imparting a full understanding thereof.

30 In the drawings:

Figure 1 is an end elevation of the improved journal box,

Fig. 2 is a similar view looking toward the opposite end thereof,

35 Fig. 3 is a vertical longitudinal section through the same,

Fig. 4 is a vertical transverse section therethrough, and

Fig. 5 is a detail in perspective of one of 40 the fiber bearing elements.

Having more particular reference to the drawings, in connection with which like reference characters will designate corresponding parts throughout the several views, the 45 improved journal box includes a substantially cylindrical shell or housing formed of metal sections 1 and 2 respectively, which sections have inwardly projecting stop lugs 3 formed on one end thereof while the remaining ends are flanged and receive screws 4 in suitable screw threaded openings formed 50 therein. Cups 5 and 6 are formed upon the upper portion of the section 1 and have openings formed in the bottoms thereof 55 which openings communicate with longitu-

dinally and transversely extending ways 7 and 8 formed in the inner face of said section, while a seat 9 is formed intermediate said cups 5 and 6 and serves to receive the upper hanger screw therein. A similar seat 60 10 is formed on the lower portion of the section 2 and serves to receive the lower hanger screw therein. The section 2 is provided with longitudinally and transversely disposed ways 11 and 12, which as will be 65 noted, receive lubricant from the upper section, inasmuch as the transverse ways 12 align with the adjacent ends of the transverse ways 8. Extending inwardly respectively from the confronting edges of the 70 members 1 and 2 are supporting ribs 16 and 17.

Seated on the inner surfaces of the sections 1 and 2 and bearing on the ribs 16 and 17 are semi-cylindrical fiber bearings 13 75 and 14, said bearings being formed with a plurality of perforations, generally indicated by the numeral 15, which perforations communicate with the lubricant distributing ways 7, 8, 11 and 12, and consequently, allow 80 lubricant to be applied over the entire bearing surfaces of the elements 13 and 14, hence, reducing friction to minimum.

It is to be noted that the semi-cylindrical bearing elements 13 and 14 bear at one end 85 against the inwardly extending stop lugs 3, while the other ends are engaged by the heads of overhanging screws 4, thus serving to positively prevent longitudinal displacement.

90 From the foregoing, it will be readily understood by persons skilled in the art that I have provided an exceedingly efficient and simple form of bearing which may be used in connection with various forms of journal boxes, and with journal boxes employed for different forms of shafts. By the use of a fiber lined journal box, that is, by the use of the bearing elements 13 and 14 instead of babbitt, brass or other similar metal commonly used heretofore, I not only provide a bearing affording less friction and consequently preventing overheating thereof, but also a bearing which when heated will not tighten or clamp upon the shaft journaled 100 therein and further, a bearing which can be readily removed and replaced with a new one in but a short space of time. Attention is directed to the fact that the bearing will 105 prove very efficient when used in connection 110

with engine crossheads or other machinery having irregular loads applied thereto and will not be distorted due to the constant stress applied thereto.

5. Manifestly, the construction shown is capable of considerable modification and such modification as is within the scope of my claims, I consider within the spirit of my invention.

10. I claim:

1. A journal box including coacting half shells having inwardly directed supporting ribs and coacting half bearings within the shell members and respectively engaging the

ribs and held thereby from contact at their 15 confronting edges.

2. A journal box including coacting half shells having inwardly directed longitudinal supporting ribs and inwardly directed stop lugs at one end, and coacting half bearings 20 within the shell members and respectively engaging the ribs, and held by the ribs from contact at their confronting edges, and means for holding said half bearings in engagement with the stop lugs.

25 In testimony whereof I affix my signature hereto.

PHILIP DUFFY.
